Primary Examiner — Darcey E Gottschalk

(57) **CLAIM**

The ornamental design for a bottle closure, as shown and described.

DESCRIPTION

FIG. 1 is a top perspective view of the bottle closure in accordance with my new design;

FIG. 2 is a front view thereof;

FIG. 3 is a back view thereof;

FIG. 4 is a left view thereof;

FIG. 5 is a right view thereof;

FIG. 6 is a top plan view thereof;

FIG. 7 is a bottom view thereof; and,

FIG. 8 is a cross-sectional view taken in the direction of the line 8-8 shown in FIG. 6.

The broken lines are shown for the purpose of illustrating parts of the article that form no part of the claim.

In FIG. 6, the dash-dot-dash broken line represents a sectional designation that forms no part of the claim.

1 Claim, 8 Drawing Sheets(56)
